US00D738027S

(12) **United States Design Patent**
Wang et al.

(10) **Patent No.:** **US D738,027 S**
(45) **Date of Patent:** **** Sep. 1, 2015**

(54) **ILLUMINATED OLED PANEL**

(71) **Applicant:** **KONINKLIJKE PHILIPS N.V.**
Eindhoven (NL)

(72) **Inventors:** **Gang Wang**, Shanghai (CN); **Joerg Knipping**, Wegberg (DE); **Jun Lu**, Shanghai (CN); **Erik Andre Hubert Wenmaekers**, Nuth (NL)

(73) **Assignee:** **KONINKLIJKE PHILIPS N.V.**
Eindhoven (NL)

(**) **Term:** **14 Years**

(21) **Appl. No.:** **29/490,962**

(22) **Filed:** **May 15, 2014**

(30) **Foreign Application Priority Data**

Nov. 18, 2013 (EM) 002346957-0001

(51) **LOC (10) Cl.** **26-03**

(52) **U.S. Cl.**

USPC **D26/85**

(58) **Field of Classification Search**

USPC D26/9, 10, 12, 13, 15, 16, 24, 51, 61, D26/72, 76, 80, 81, 85, 86, 88, 89, 90, 113, D26/118, 119, 120, 122, 124, 128, 129, 138, D26/143, 144; D13/180; D10/18, 21, 24, D10/25, 27, 28, 46, 93, 104.1; D23/261; D7/624.1, 624.2

Primary Examiner — Kevin Rudzinski

Assistant Examiner — Sean D Lough

(57) **CLAIM**

The ornamental design for a illuminated OLED panel, as shown.

DESCRIPTION

FIG. 1 is a perspective view showing my design;

FIG. 2 is a front elevational view thereof;

FIG. 3 is a rear elevational view thereof;

FIG. 4 is a right side elevational view thereof;

FIG. 5 is a left side elevational view thereof;

FIG. 6 is a top plan view thereof; and,

FIG. 7 is a bottom plan view thereof.

1 Claim, 4 Drawing Sheets
